FUSIBLE HOLDING ARM FOR DOOR CLOSERS

David R. Lasier, Princeton, Ill., assignor to LCN Closers, Inc., Princeton, Ill., a corporation of Illinois

Application March 14, 1958, Serial No. 721,563

3 Claims. (Cl. 189—45)

This invention relates, as indicated, to an improved hold-open device for doors, and more particularly to a hold-open device having an automatic release for rendering it ineffective in case of fire.

It is an object of this invention to provide a holding arm which is releasable when exposed to heat from fires so that the door may be closed automatically to cut off drafts and the communication between rooms in order to prevent or deter the spreading of fires.

It is a further object of this invention to provide a reliable hold-open device which depends for its releasing action upon a fusible link of well-known construction which will fuse at a predetermined temperature.

It is yet another object of the invention to provide a releasable holding device having a mechanism for rapidly closing the doors.

It is still another object of the invention to provide a releasable hold-open device of the type above described which is simple in construction and is easily and inexpensively manufactured and yet which is highly efficient, durable and dependable in service.

It is yet another object of the invention to provide a holding device for doors and the like which may be used separately or in conjunction with a checking and closing mechanism.

Further objects and advantages of this invention will become evident as the description proceeds and from an examination of the accompanying drawing which illustrates several embodiments of the invention and in which similar numerals refer to similar parts throughout the several views.

In the drawing:

Figure 1 is a plan view of a door hold-open device embodying the invention.

Figure 2 is a fragmentary elevational view partly in section of the device shown in Fig. 1.

Figure 3 is a fragmentary view of a modified form of the invention.

Referring now to the drawings, it will be seen that the hold-open device here illustrated has a primary pivot which is used for the normal opening and closing of the door or other closure. The primary pivot is a stud indicated generally by reference numeral 10 having threaded extremities 11 and 12 and a non-circular integral central section 14 which may be in the form of a square outline. A soffit plate 16, adapted to be secured to a door frame, is provided with internal threads 17 for receiving the threads on extremity 11 of the stud 10.

A friction head 19 is mounted on the non-circular section 14 of the stud 10. The friction head has an upper friction face 20 for engaging the lower face of soffit plate 16. An aperture 21 in the friction head is of a configuration conforming to the outline of the central section 14 of stud 10, so that the friction head and stud are non-rotatable with respect to each other and move as a single unit. As the forearm 22 rotates when the door is opened and closed, the stud 10 is screwed into and out of the threaded aperture 17 in the soffit plate. As the stud

2

moves in and out of the soffit plate, the friction head 19 is moved into and out of engagement with the lower face of the soffit plate. When the face of the friction head is moved into binding engagement with the lower face of the soffit plate, the two members maintain the door in a hold-open position.

On the lower portion of the stud 10 is mounted a booster spring container 24 having an aperture 25 conforming to the outline of the central section of the stud 10 so as to be non-rotatable with respect to the stud and move as a unit therewith.

A nut 28 is threaded on the lower extremity 12 of stud 10. It will be noted that the stud, friction head 19 and the booster spring container 24 form a rotatable assembly 15 unit which is rotated by arm 22, under normal conditions, as the door is opened and closed by the turning movements of the threaded end 11 of stud 10 in soffit plate 16.

Projecting upwardly from container 24 is a boss 26 with a cylindrical outer surface. A circular opening 30 in forearm 22 is journaled on boss 26, so that the forearm can rotate independently of and relative to the unitary assembly described hereinabove, under certain conditions.

In normal operations the forearm is prevented from independent movements by a deformable resilient spring arm 32. One end of the spring arm is secured to friction head 19 by any suitable means, such as a rivet 33. The other end of the spring arm extends along the upper side of the forearm and when released assumes a position spaced therefrom, as shown by the dotted lines in Figure 30 2.

Under ordinary conditions the spring arm is releasably locked to the forearm. The end of the spring arm has a socket in the form of an opening 34 for receiving a stud 36 mounted on the forearm. The spring arm is deformed 35 and held over the stud, so that the forearm is locked thereto. Since the spring arm is locked to the forearm, swinging movements of the door causes the forearm to move the rotatable assembly unit with the stud 10 as the door is opened and closed.

In order to maintain the spring arm 32 on the stud 36 a fusible link mechanism is provided. As shown in the drawing, this may include a lever 40 pivotally mounted on a pin 41 in mounting block 42 on the upper side of the forearm 22. The lever 40 has an arm 43 for engaging the end of the spring arm and a lower leg 44 which projects through an opening 45 in the forearm. In normal operation, the arm 43 of the lever engages the spring arm 32 to hold it over the stud 36 and is maintained in this position by a spring 48 and fusible link 49 connected in series to a post 47 depending from the lower side of the forearm.

A booster spring 51 is mounted in container 24. One end 52 of the spring is secured to forearm 22 and the other end of the spring is fastened to container 24. The spring is biased and preloaded to move the forearm 22 relative to the container 24 to aid in closing the door, when link 49 is fused and spring arm 32 released to permit free and independent movements of the forearm 22.

From the foregoing, operation of the device is believed to be apparent. The primary pivot between the soffit plate 16 and the forearm 22 is on the stud 10. The forearm, since it is held in engagement with the stud by the spring arm 32, turns the stud in and out of the soffit plate as the door opens and closes. When the door is opened 140 to 180 degrees, as adjusted, the friction head face 20 binds the lower surface of the soffit plate 16 to maintain the door in an open position.

When the link 49 fuses, the lever 40 is released, permitting the spring arm 32 to be separated from the forearm to a position, as shown by the dotted lines in Figure 70 2. The removal of the spring arm from the forearm permits the forearm to swivel freely about a secondary pivot

on the boss 26 of container 24. The secondary pivot allows the door to be easily and fully closed.

The booster spring 51 aids in moving the door to a closed position when the spring arm is released and the forearm moves independently of the stud. The booster spring 51 is preloaded and under tension, so that as soon as the forearm is permitted independent movement, it is quickly rotated to immediately start moving the door to closed position.

In the modification shown in Figure 3, the spring arm 62 is provided with a socket in the form of a recess to receive stud 66 on the forearm 22. In other respects the structure and operation is the same as the device shown in Figures 1 and 2.

This application is a continuation-in-part of application Serial Number 442,012, filed July 8, 1954.

In the drawings and specification, there has been set forth a preferred embodiment of the invention, and although specific terms are employed, they are used in a generic and descriptive sense only, and not for purposes of limitation. Changes in form and in proportion of parts, as well as substitution of equivalents, are contemplated, as circumstances may suggest or render expedient, without departing from the spirit or scope of this invention as further defined in the following claims.

I claim:

1. A door holder comprising a stationary plate member, a rotatable unit, a screw connection between said stationary plate member and said rotatable unit to move the same relatively toward and away from each other, a friction face on said stationary plate, a friction face on said rotatable unit opposed to said stationary plate friction face for frictional engagement and disengagement therewith as said rotatable unit is moved toward and away from said stationary plate, a cylindrical member on said rotatable unit, an arm member rotatably mounted on said cylindrical member, a deformable resilient spring arm rigidly connected to said rotatable unit biased to a position spaced from said arm member, releasable means including a fusible link for releasably locking said spring arm in a deformed position to said arm member, and a spring means between said arm member and said rotat-

able unit to move the arm member relative to said rotatable unit when the latter means is released.

2. A door holder comprising a stationary plate member, a rotatable unit, a screw connection between said stationary plate member and said rotatable unit to move the same relatively toward and away from each other, a friction face on said stationary plate, a friction face on said rotatable unit opposed to said stationary plate friction face for frictional engagement and disengagement therewith as said rotatable unit is moved toward and away from said stationary plate, a cylindrical member on said rotatable unit, an arm member rotatably mounted on said cylindrical member, locking means for releasably connecting said rotatable unit to said arm member, means including a fusible link for releasing said latter means, and a spring means between said arm member and said rotatable unit to move the arm member relative to said rotatable unit when said locking means is released.

3. A door holder comprising a stationary plate member, a rotatable unit, a screw connection between said stationary plate member and said rotatable unit to move the same relatively toward and away from each other, a friction face on said stationary plate, a friction face on said rotatable unit opposed to said stationary plate friction face for frictional engagement and disengagement therewith as said rotatable unit is moved toward and away from said stationary plate, a cylindrical member on said rotatable unit, an arm member rotatably mounted on said cylindrical member, locking means including a deformable resilient spring arm rigidly connected to said rotatable unit for releasably connecting said rotatable unit to said arm member, means including a fusible link for releasing said latter means, and a spring means between said arm member and said rotatable unit to move said arm member relative to said rotatable unit when said locking means is released.
